UNITED STATES PATENT OFFICE.

JOSEPH RICE, OF CHICAGO, ILLINOIS, ASSIGNOR TO ELEVATOR COMPANY OF AMERICA, OF CHICAGO, ILLINOIS, A CORPORATION OF ILLINOIS.

DOOR-CONTROLLING MECHANISM FOR ELEVATORS.

Application filed July 14, 1926. Serial No 122,368.

My invention relates to door controlling mechanism for elevators and has for its object the provision of improved means for preventing the opening of hatch doors unless the elevator is in proper position to be aligned with the door which is to be opened.

My invention concerns itself primarily with the provision of means in which a downwardly moving element carried by the car is adapted to strike the door controlled mechanism in its path when said controlling element is in its actuating position due to the fact that the car is not under headway.

My invention concerns itself with an improved mechanism which provides a substantially rather unyielding well backed abutment which is adapted to actuate the various door locking mechanisms with which it may come into contact, which door locking mechanisms are mounted in the hatchway.

It is a further object of my invention to provide a sliding abutment of the character which is so arranged that its operation may be noiseless.

I will describe one form which my invention may take more in detail by referring to the accompanying drawing in which:

Fig. 1 shows a fragmentary portion of an elevator car having my improved device in position and shown as cooperating with a door controlled mechanism;

Fig. 2 is a fragmentary sectional view on lines 2—2 of Fig. 1; and

Fig. 3 is a diagrammatic circuit arrangement for illustrating the electrical features involved.

Referring more particularly to Figs. 1 and 2, I show a car 10 which is provided with my improved movable abutment 11 which abutment is adapted to be either in the limiting position shown in Fig. 1 or in a retracted position whenever it is drawn into that retracted position by an electro-magnet 12 also provided upon the car. The abutment 11 is designed to cooperate with a door controlled mechanism consisting of a lever 13, there being such a lever together with with its accompanying parts at each floor level for each hatch door. The lever 13 is pivoted upon a stem 14 and carries a roller 15 which cooperates with the shoes 16 provided upon the abutment 11. The spring 17 normally pushes the lever 13

against an adjustable stop 18. The lever 13 through the agency of instrumentalities, 55 which it is not thought necessary to illustrate or explain herein, controls a suitable lock so that when the lever 13 is in the position shown in Fig. 1, the corresponding door may be opened. If on the contrary the lever 13 is in this alternative position when its tail piece 19 rests against the stop 18, then the corresponding door is locked and cannot be opened.

The magnet 12 may for instance be included near the general control circuit through the agency of which the car is operated which control circuit is shown in Fig. 3 as receiving its current from the generator 20, and which control circuit is controlled by 70 the handle 21 in the car. Thus, whenever the car is operated as when the lever 21 is in association with the contact posts 22, 23, 24 or the like, then the magnet 12 is energized, but should the power which operates the car 75 be off, then the magnet 12 is deenergized. Whenever the magnet 12 is energized it raises the abutments 11 and when it is deenergized, it permits it to fall into the position shown in Fig. 1.

From this it will be clear that so long as the car is passing the various floors, the current being on, that the abutment 12 is retracted and does not touch the various rollers 15 which it passes. Should the operator, 85 however, when he is about to arrive at a floor, turn off the current, then the abutment 11 drops and is in position to actuate the roller 15 corresponding to that particular floor at which the car is to stop.

In the diagrammatic illustration of Fig. 3, the conductors 25 and 26 lead to the motor actuating mechanism which actually moves the car. The drawing of Fig. 3 is to be taken purely for illustrative purpose to show 95 the general relationship of the magnet 12 and is not to be understood as setting forth any particular circuit for controlling the car. My invention as above stated concerns itself primarily with the construction, arrangement, mounting, and manner of operating 100 the abutment 11. The abutment 11 consists in addition to the shoe 16 of the plate shaped slide 27 which on one side slides in the U groove provided in the bearing element 28 105 and has sliding engagement at its other

side with a T-shaped groove provided in the bearing element 29. For this purpose the slide 27 has a T shaped extremity 30 at its one side, all of which is more clearly apparent from Fig. 2. The bearings 28 and 29 are preferably held together through the agency of the back 31 and are suitably mounted upon a strip 32 provided upon the car 10 through the agency of the bolts 33 and 34.

It will thus be seen that the slide 27 has a movement which is slightly inclined from the vertical. The advantage of this is that the weight of the slide together with its shoe and other cooperating parts may have a material influence in providing the necessary stability, and it will also be seen that the bearing portion 29 backs up the slide in a line which is only slightly inclined from a line at right angle to the thrust action by the rollers 15. The bearing portion 29 thus amply backs up the slide 27 against the pressure of the roller 15. A stop 35 may be provided for precautionary purpose and it is also desirable to provide a plate 36 at the upper extremity of the bearing portions 28 and 29 which plate prevents the slide 27 from slipping upwardly beyond its proper position and also furnishes a bearing for the stem 37 which stem is secured to the said slide 27. The stem 37 is by means of the eye 38 and the chain 39 connected to a lever 40 which lever at its opposite extremity is connected to the plunger 41 cooperated with the solenoid 12.

In order to provide a noiseless operation, I provide certain buffers which prevent the clattering noise usually due to the locking parts when moved and brought into contact. To this end I provide a buffer spring 42 which prevents a too great retraction of the slide 27 and I provide a further buffer spring 43 which acts to prevent the clattering which might be due to the plunger 41 and its associated parts. These springs serve as buffers although they do not limit the actual movement of the moving parts.

From what has thus been described, the nature of my invention will be readily apparent to those skilled in the art and it will also be understood that modifications may be made from the specific disclosure herein without departing from the spirit of my invention.

Having thus described one form which my invention may take, what I claim as new and desire to secure by United States Letters Patent is:

1. In a door control apparatus for elevators the combination with an elevator car having a movable abutment structure, of door control mechanism having an element adapted when said abutment structure is in its actuating position to be moved by said structure into its door-release position, said

abutment structure including a slide mounted so as to fall when released, by the action of gravity into its actuating position, and electro-magnetic means adapted to retract said slide.

2. In a door control apparatus for elevators the combination with an elevator car having a movable abutment structure, of door control mechanism having an element adapted when said abutment structure is in its actuating position to be moved by said structure into its door-release position, said abutment structure including a slide mounted so as to fall when released, by the action of gravity into its actuating position, electro-magnetic means adapted to retract said slide, and double acting buffers to deaden the noise due to the moving parts of said abutment structure.

3. In a door control apparatus for elevators, the combination with an elevator car having a movable abutment structure, of door control mechanism having an element adapted when said abutment structure is in its actuating position to be moved by said structure into its door-release position, said abutment structure including a slide mounted so as to fall when released, by the action of gravity into its actuating position, electro-magnetic means adapted to retract said slide, and double acting spring buffers to deaden the noise due to the moving parts of said abutment structure.

4. In a door control apparatus for elevators the combination with an elevator car having a movable abutment structure, of door control mechanism having an element adapted when said abutment structure is in its actuating position to be moved by said structure into its door-release position, said abutment structure including a slide mounted so as to fall when released, by the action of gravity into its actuating position, guides for said slide, and electro-magnetic means adapted to retract said slide.

5. In a door control apparatus for elevators the combination with an elevator car having a movable abutment structure, of door control mechanism having an element adapted when said abutment structure is in its actuating position to be moved by said structure into its door-release position, said abutment structure including a slide mounted so as to fall when released, by the action of gravity into its actuating position, guides for said slide, electro-magnetic means adapted to retract said slide, and double acting buffers to deaden the noise due to the moving parts of said abutment structure.

6. In a door control apparatus for elevators the combination with an elevator car having a movable abutment structure, of door control mechanism having an element adapted when said abutment structure is in its actuating position to be moved by said

structure into its door-release-position, said abutment structure including a slide mounted so as to fall when released, by the action of gravity into its actuating position, guides for said slide, one of said guides being substantially T-shaped, and electro-magnetic means adapted to retract said slide.

7. In a door control apparatus for elevators the combination with an elevator car 10 having a movable abutment structure, of door control mechanism having an element adapted when said abutment structure is in its actuating position to be moved by said structure into its door-release position, said 15 abutment structure including a slide mounted so as to fall when released, by the action of gravity into its actuating position, guides for said slide, one of said guides being substantially T-shaped, electro-magnetic means 20 adapted to retract said slide, and double acting buffers to deaden the noise due to the moving parts of said abutment structure.

8. In a door control apparatus for elevators the combination with an elevator car having 25 a movable abutment structure, of door control mechanism having an element adapted when said abutment structure is in its actuating position to be moved by said structure into its door-release position, said abutment 30 structure including a slide mounted so as to fall when released, by the action of gravity into its actuating position, guides for said slide, one of said guides being substantially T-shaped, stops provided in association with said guides to limit the 35

movement of said slide, and electro-magnetic means adapted to retract said slide.

9. In a door control apparatus for elevators the combination with an elevator car having a movable abutment structure, of door control mechanism having an element adapted when said abutment structure is in its actuating position to be moved by said structure into its door-release position, said 40 abutment structure including a slide mounted so as to fall when released, by the action of gravity into its actuating position, guides for said slide, one of said guides being substantially T-shaped, stops provided in association with said guides to limit the movement of said slide, electro-magnetic means adapted to retract said slide, and double acting buffers to deaden the noise due to the moving parts of said abutment structure.

10. In a door control apparatus for elevators the combination with an elevator car having a movable abutment structure, of door control mechanism having an element adapted when said abutment structure is in its actuating position to be moved by said structure into its door-release position, said 45 abutment structure including a slide adapted to slide into its actuating position along a line slightly inclined to the vertical, and electro-magnetic means adapted to retract 50 said slide.

In witness whereof, I hereunto subscribe my name this 21st day of June, A. D. 1926.

JOSEPH RICE.
